UNITED STATES PATENT OFFICE.

CHARLES G. JORDON, OF CATLIN, COLORADO.

CANTEEN.

SPECIFICATION forming part of Letters Patent No. 273,097, dated February 27, 1883.

Application filed August 7, 1882. (No model.)

To all whom it may concern:

Be it known that I, CHARLES G. JORDON, of Catlin, in the county of Bent and State of Colorado, have invented a new and useful Improvement in Canteens, of which the following is a full, clear, and exact description.

Reference is to be had to the accompanying drawings, forming part of this specification, in which similar letters of reference indicate corresponding parts in all the figures.

Figure 1 represents a view in perspective of a canteen constructed in accordance with my invention, as removed from a case which is combined with it, and showing a portion of the cloth covering removed. Fig. 2 is a view in perspective of said case with its attached straps, and showing a portion of its cloth covering removed. Fig. 3 is a side view of the case with attached straps; and Fig. 4, a transverse vertical section, upon a larger scale, of the canteen and case in which it sits combined.

The invention consists in a canteen, water-cooler, jug, or vessel for holding and carrying liquids for immediate or daily use, in which the body of the vessel, made of metal or other suitable material to give it stiffness, is provided or riddled with perforations, and has combined with it a cloth or other like absorbent covering, whereby evaporation is promoted and the contents of the vessel kept cool without sensible or material wetting of the person carrying the canteen or vessel.

The invention also includes a shoe or case in which the lower portion of the canteen sits, for the purpose of preventing the damp cloth covering of the perforated canteen from coming in contact with the person, which case may also be used as a drinking-cup.

A is a tin or metal canteen, which may be similar in shape and general construction to canteens heretofore in use, and, like them, is covered with cloth, and has the usual screw-nozzle, b. The upper portion of the body of this canteen, however, or it may be the entire body, if desired, unlike other canteens, is riddled with perforations c. The covering d of the canteen should be of heavy cloth or other equivalent fibrous and flexible absorbent material, and should be made to fit the canteen nicely and snugly. A perforated canteen thus clothed provides for a moderate but ample ab-

sorption of the liquid within it, and for evaporation from its clothed surface to keep the contents of the canteen cool, and in this respect it is but little, if any, inferior to a bag or sack made wholly of canvas or cloth, while it is greatly superior thereto in strength and in being protected by its inflexible body from being ruptured and from yielding to outside pressure, which keeps up a constant dripping, wetting the clothes of the person, and, in fact, everything it comes in contact with, when such bag or sack is hung on the shoulders. The perforations in the body of the canteen A should be arranged and adapted to keep up a self-feeding supply of moisture to the general surface of the covering commensurate with the evaporation which takes place in ordinary usage, so as to avoid all unnecessary dripping, and in this respect due consideration should be had to the increased disturbance of the contents produced by the person wearing the canteen when walking or riding. If necessary, the canteen may be inverted occasionally for a few moments at a time to keep its covering properly saturated.

To catch any drip from the canteen that may occur, and to provide for returning liquid so collected back to the canteen, as well as to prevent the damp cloth covering the canteen from coming in contact with the person, the lower portion of the canteen is arranged to sit in a metal or other suitable shoe or case, B, which may also, when desired, be used as a drinking-cup, it being detachable from the canteen. This case is also preferably covered with cloth e, and is provided with hooks f, for attachment of the straps g, by which the canteen is suspended from the person. Attached also to the cloth d of the canteen; on one side, is a light strap, h, which engages with a buckle or button, i, secured on the cloth covering e of the case, for the purpose of holding the canteen and case firmly together.

The case B may, if desired, be dispensed with, especially in extremely hot weather, and the carrying-straps g be attached directly to the canteen.

In the drawings only the upper portion of the body of the canteen is shown perforated and covered with cloth, and the lower portion made close, which prevents drip at the base.

Having thus fully described my invention, I claim as new and desire to secure by Letters Patent—

1. A canteen, water-cooler, jug, or vessel, made of metal or other stiff material, and having a portion or the whole of its body provided or riddled with perforations and clothed with a covering of cloth or other fibrous and flexible absorbent material, whereby evaporation is promoted and the liquid contents of the vessel are kept cool, substantially as specified.

2. The combination, with a perforated canteen of rigid material, having a cloth or other similar absorbent covering, of a shoe or case constructed to detachably receive the canteen, at the lower portion of its body, within it, whereby the damp covering of the canteen is restrained from coming in contact with the person, drip from the canteen is caught by the case, and the case may be used as a drinking-cup, essentially as herein set forth.

3. The case B, for holding the canteen, having a covering, e, of fibrous material, and the straps g, for suspending the canteen, secured to said case, substantially as specified.

4. The combination, with the cloth covering d of the perforated canteen, and the cloth covering e of the case B, of the strap h, and the buckle or button i, for firmly holding the canteen and case together, essentially as described.

5. The combination of the perforated canteen-body A, of rigid material, the cloth covering d, applied thereto, the cloth-covered shoe or case B, having the strap g, by which the canteen is carried or suspended, attached to it, and the strap and buckle or button fastening h i, substantially as specified.

CHARLES GRIFFITH JORDON.
